SELECTOR MECHANISM FOR JACQUARD-PUNCHING MACHINE AND THE LIKE

Frank B. Ware, Moorestown, N. J., assignor to Tartan Knitting Mills, Inc., Philadelphia, Pa., a corporation of Pennsylvania

Application September 9, 1952, Serial No. 308,577

3 Claims. (Cl. 164—112)

The present invention relates to certain new and useful improvements in so-called card-punching machines for punching the holes in the pattern-card or in the pattern-paper or pattern-roll or band used in controlling the pattern mechanism of a knitting machine (or other textile machine) such as a Jacquard type knitting machine and other Jacquard controlled textile machines.

The present invention relates to a mechanism for insuring the non-overlapping or non-duplicating selection of punches, for the successive colors of the same course, and also for minimizing the labor involved in making the selection of punches.

In pattern-punching machines of this general class (including but not limited to the 70 lever duplicator design-punching machine made by the Jacquard Knitting Machine Company of Philadelphia and described in its 1946 instructions booklet), the punch-selector bars or levers are selectively interposed between depressor-head or press-bar of the punch-mechanism and the hole-punching pins. Each punch-selector bar is generally provided with a rear terminal knob or up-standing handle-like portion or "tab," by means of which the punch-selector bar can be manually pushed in, into operative position. While these "tabs" are here referred to as being on rear ends of the punch-selector bars, yet in common parlance the "tab" end of the heretofore conventional machine was referred to as the "front" of the machine, because it is at this end of the machine that the operator must be in order to operate the machine. These upstanding tabs were usually numbered (in groups of ten) from 1 to 10, and this numbering is repeated with every ten bars. After the bars selected (for a particular color in a course of knitting) are pushed in, the punching mechanism of the machine is actuated or moved through one complete cycle, by manually turning a handwheel through one revolution.

During the last portion of the revolution of the handwheel (in the heretofore conventional design-punching machine) the theretofore selected bars were retracted by hand wheel and returned to their original inoperative positions. This same turning of the hand-wheel also advanced the pattern paper or band to the next position. The operator then selected the next group of bars (according to the pattern drawing) for the next color in the same course, and the hand-wheel was again turned and the punching operation thus performed on the next position of the paper; and so for the third color another group of these bars are selected and the punching operation there performed for the third position of the paper (and so forth for a fourth color, if there be a fourth color in the same course).

By this prior practice the operator had to be careful not to select the same bar twice within the same course (unless for making a half stitch). However, liability of error was very great because each time a new set of bars was to be selected for the same course, all the theretofore selected bars-and-tabs were in their retracted or initial position. Thus, great care had to be exercised so as not unintentionally, or by mistake, to select one of

2

the bars which had just been used for a previous color in the same course.

By the present invention the selector tabs at the rear ends of selector bars are entirely eliminated, and a series of selector discs, carried upon a common shaft, are placed in advance of and in operative alignment with the ends of the heretofore conventional selector-bars; each disc being rotatably mounted upon the shaft and having a selector tab and also a pusher-projection and also having a normalizing notch, and retainer notches in its periphery for retaining each disc in one of their three operative positions.

The disc-bearing shaft is, in turn, journaled in a pair of journal blocks which are slidably mounted in horizontal guide-ways and are reciprocable to and fro, so as to reciprocate the entire group of discs and push them against the ends of the selector bars; the pair of journal blocks being rigidly interconnected through a connecting yoke-bar in front of the disc, which yoke-bar carries spring-pressed disc-retainer balls (one for each disc); the two journal blocks and the yoke-bar forming a generally U-shaped frame in which the discs and disc-shaft are journaled.

By pushing (turning) as by manually through the use of a hand stylus or by other means such as through a master pattern strip (or card), which has been pre-punched the selector-tabs of the desired discs forwardly, to their first position, the push-projection of the corresponding disc is turned into alignment with its punch-selector bar, so that when the entire group of discs is advanced against the punch-selector bars, only those bars will be pushed into their operative positions whose discs have been so turned. Upon the return stroke of the entire group of discs, the theretofore selected and turned selector-tabs strike a pivoted overhead pawl-bar, which then further turns the theretofore selected discs until the push-projections thereof are below the level of the punch-selector bars. This overhead pawl-bar is pivotally mounted on the stationary frame member which provides the aforesaid guideways, so that the pawl-bar may raise upwardly slightly to permit the selector-tabs of the discs to be turned freely and then to be advanced freely underneath the pawl-bar (first on the manual turning and subsequent advancing stroke of the discs). The pawl-bar then drops behind the tabs and so engages them on the return stroke of the discs, so as to further turn the selected discs into their inoperative positions on the return-stroke.

In this manner the set of discs selected for any color are put out of action and beyond the reach of the operator when he proceeds to select discs for the next color in the same course.

The last color to be selected for the course ordinarily involves all of the remaining needles (or heddles) for which the pattern-hole-punches had not been selected for the previous colors within the same course. By the machine or apparatus of the present invention this last color need not be selected at all by the individual selection of the remaining discs (by the individual and separate engagement, by the operator of the remaining selector-tabs on such discs) but, instead, a finishing-lever and finishing-bar is provided, journaled upon the disc-bearing shaft, and the single deflection of the finishing-lever turns into their operative positions all the discs not theretofore used.

When all discs have been thus turned, then on the next return-stroke of the disc-group a spring-urged pivoted pawl-bar beneath the disc-group enters the normalizing notches in all the discs (now aligned for the first time), so that upon the last portion of such return-stroke of the disc-group, their engagement with this lower pawl-bar causes all discs to be counter-rotated to their initial or starting positions for the next course.

The present invention also includes other mechanisms and features for fuller control and guidance in punching cards; all as will be more fully described hereinafter and as shown in the accompanying drawings, in which like reference characters indicate like parts.

Figure 1 represents a left side elevational view of a card-punching machine embodying the present invention, with some of the lower treadle portions omitted.

Figure 2 represents a right-side elevational view of the same.

Figure 3 represents a front elevational view of the same with part of the pattern-chart-guide broken away and with some of the lower portions of the machine also broken away.

Figure 4 represents a vertical section taken on line 15 4-4 of Figure 3.

Figure 4a represents a view of a disc 83, similar to that shown in Figure 4, but with the disc advanced to its first or operative position.

Figure 4b represents a similar view of the disc advanced 20 to its second and inoperative position.

Figure 5 represents a section on line 5-5 of Figure 1.

Figure 6 represents a top plan view of the control mechanism of the present invention.

Figure 7 represents a bottom plan view of the right- 25 signal shown in Figure 6.

Figure 8 represents a perspective view, partly in cross section of one of the discs and the finishing bar and related elements.

Figure 9 represents a front elevational view of the 30 vertical magazine and guide for holding and feeding the punching diagram (a line at a time) so as to expose to view one line at a time in juxtaposition to the turn-projections on the discs.

Figure 10 represents a section on line 10-10 of Figure 9.

Figure 11 represents a section on line 11-11 of Figure 9.

Figure 12 represents a side elevational view of the clutch mechanism intervening the power-driven pulley (which is idle on the main shaft) and the main shaft of the machine, and the operating mechanism for activating the clutch.

Figure 13 represents a side elevational view of the same mechanism viewed from a position 180° from that shown in Figure 12.

Figure 14 represents a side elevational view on a somewhat larger scale, of the clutch operating rod and treadle and the rod-clutch.

Figure 15 represents a top plan view of the same.

Figure 16 represents an exploded view of the parts of 50 the rod-clutch mechanism.

Figure 17 represents a section on line 17-17 of Figure 15 with a rod shown clutched.

Figure 18 represents a similar cross-sectional view with the rod shown released.

Figure 19 represents an inside elevational view of the drive wheel and clutch viewed in the direction of the arrow 221 in Figure 21.

Figure 20 represents a top elevational view of the drive wheel and clutch, with the drive wheel or belt shifter partly broken away, and parts including the handle removed for the sake of clarity.

Figure 21 represents a section on line 21-21 of Figure 20.

Figure 22 (on sheet 4 of the drawings) represents a side elevational view of the operating rod or tool 150, shown in relation to the bar 135 of Figure 4.

Referring to Figures 1 and 4, on the left side is shown a heretofore conventional card-punching machine such as made by the Jacquard Knitting Machine Company of Philadelphia, to which my present invention may be applied (although my present invention may be applied to other card-punching machines).

While reference is made to "card" punching, it is to be understood, of course, that the term "card" includes a

continuous web of paper or highly sized form-retaining cloth (similar to tracing cloth but perhaps stouter and more durable) into which the successive lines of holes are punched, in accordance with the pattern or design diagram; such punched web being then usable to control the knitting machine or other textile machine equipped with the so-called Jacquard mechanism.

For perhaps a fuller and clearer understanding of the present invention and its relationship to the heretofore 10 conventional card-punching machine, a brief preliminary description of the heretofore conventional card-punching machine is now given.

The frame 25 of the card-punching machine carries the main shaft 26 journaled therein, in any suitable journal blocks or pedestals. Above the main shaft 26 a punch block 27 is slidably mounted within vertical side-guides or ways of the vertical punch-block frame 28; the latter is mounted upon the main frame 25. A pair of eccentrics 29 are mounted upon and keyed to the shaft 26, beyond the respective ends of the punch-block 27 and eccentric-straps 30, with intervening bearings 31 are mounted upon the eccentrics; said eccentric straps having connecting-rod extensions 32 thereon which are pivoted, by means of the pivots 33, to the ends of the punch-block 27, so as to move the punch-block 27 down and up with each revolution of the shaft 26.

The lower die 34, having a series of punch-holes 35 therein, one for each knitting-needle or loom-heddle, is supported in the main frame 25. Immediately above it, but with a clearance sufficient for the passage of the punch-paper or punch-card, is a lower punch-guide 36, and above that is the upper punch guide 37, with holes therein in alignment with the holes 35 in the die 34. A punch-pin or commonly called "punch" 38 is slidably mounted in each pair of lower and upper guide-holes in the punch-guides 36 and 37. Each punch 38 has an upper head 39. A retractor-plate 40 is carried on the bottom of the punch block 27 with a hole or slot therein corresponding to each punch 38, and the retractor-plate 40 serves to raise the punches 38 which have been depressed, that is, to raise them to their upper position, when the punch block is raised.

A presser-bar 41 is carried on the front face of the punch-block 27 with a downwardly bending lip 42 which is adapted to engage and to depress whichever selector-bars 45 are projected into its path while the punch-block 27 and presser-bar 41 are in their inoperative or upper positions.

The selector-bars 43 are arranged side by side, there being one selector-bar for each position (a needle or a heddle to be controlled in a row or course). The selector-bars 43 are guided by a pair of aligned comb-like member 44 and 45 whose teeth 46 and 47 are spaced apart just sufficiently to receive the relatively thin flat selector-bars 43 with sufficient clearance to permit the selector-bars 43 to slide to and fro in the slits or slots provided by said teeth. The selector-bars 43 are also provided with an elongated pivot aperture 48 through which a common pivot-bar 49 extends, about which the selector-bars 43 may be tilted when in their punching positions shown in Figure 4; each selector-bar 43 having a helical tension spring 50 connected thereto at its spring-anchor- 60 age 51, while the other end of the spring is connected to a stationary spring-anchorage 52. The springs 50 serve to retract the selector-bars both vertically in the direction of the arrow 53 as well as horizontally in the direction of the arrow 54, when the presser-bar 41 is raised to its upper position.

While the presser-bar 41 and punch-block 27 are in their upper position, the selector bars 43 selected for a particular color in the course are advanced in the direction of the arrow 55 so as to bring the ends 56 thereof beneath the presser-bar. Each of the selector-bars 43 is directly above and in vertical alignment with a head 39 of a corresponding punch 38, so when the presser-bar 41 descends, carrying with it and downwardly-tilting the

ends 56 of the advanced selector-bars 43, the corresponding punches will be pushed down through the punch paper or web or "card" 57 which is fed from a roll underneath (not shown) between the die 34 and punch-guide 36 and down over the roller 58 which is advanced, intermittently, at a pre-determined spacing, after each down-stroke of the punch-block 27, by means of the Geneva wheel 59 carried at one end of said roller; said Geneva wheel being driven and locked by means of a corresponding actuator wheel 60, which, in turn, is geared to the main or drive shaft 26 through the pair of pinions 61 and 62. An idle press-roll 63 serves to press the paper 57 against the feed-roll or propelling-roll 58.

The following is a description of the control mechanism and other related mechanisms of the present invention in relation to the above described punching machine.

The frame 71 of the control mechanism of the present invention may be affixed to the frame 25 by means of a flange 72 bolted or otherwise secured to the frame 25. Upon the frame 71 pairs of horizontal guide-rails 73 and 74 are mounted upon posts 75 and 76. A generally U-shaped slide-frame 77 having pairs of guide-rollers or wheels 78 and 79 pivotally mounted to the outer surfaces of the opposite legs of the U, is supported between the rails 73 and 74 by means of the wheels 78 and 79 which project between said rails and serve to support the U-shaped slide-frame for to and fro horizontal movement in the direction of the arrows 80 and 81 (Figure 2). A central shaft 82 is mounted in and across the two legs of the U-frame 77. Upon the shaft or pivot bar 82 the control-discs 83 are pivotally mounted, each capable of being turned independently of the other. Each disc 83 is provided with a push-projection 84 and a selector-projection 85. A return-notch 86 is provided at each disc adapted to be engaged by the return-pawl 87 when the U-frame 77 is on its return stroke after all the discs 83 have been turned (so that the pawl 87 may enter all the notches 86). Retainer notches 88, 89 and 90 are provided in the outer periphery of each disc, into which a retainer-ball 92 may enter under the influence of the spring 93 housed and confined in a corresponding hole in the base-bar 94 of the U-shaped slide-frame 77; the back ends of the springs 93 being held and buttressed by the cover-plate 95 which covers the outer ends of all the spring holes; the plate 95 being held in place by screws entering the base-bar or block 94. The notches 88, 89 and 90 correspond to the three positions of the discs. Notch 88 corresponds to the retracted or initial position of the discs shown in Figure 4, wherein the push-projection 84 is just above and not in alignment with the selector bar 43. The notch 89 corresponds to the first advance-position of the push-projection 84, in which position it is in alignment with its corresponding selector-bar 43. The notch 90 corresponds to the second advance-position or the down-position of the push-projection 84, namely, the position in which the push projection 84 is just below and out of alignment with the selector bar 43 (and in which position the return-notch 86 has closely approached the pawl-bar 87).

A shaft 97 is journalled in and extends through the frame 71 and has at each of its outer ends a lever 98 affixed thereto and keyed or pinned thereto. The upper ends of each lever 98 are provided with a longitudinal slot 99 which receives the reduced outer ends of the shaft and pivot 82 as indicated in Figures 1, 2 and 5. The lever 98 on one or both sides of the machine is connected by means of a connecting rod 100 (pivoted to the lever at 101) to the crank pin 102 carried by the end of the crank 103, which, in turn, is carried on the end of the main or drive shaft 26 and the angle of the crank 103 on the drive shaft 26 is such that the connecting rod 100 will be moved in the direction of the arrow 104 when the press-bar 41 has cleared the ends 56 of the selectors 43 and will move in the direction of the arrow 105 while the press bar 41 is on its down stroke (see Figure 1).

For purposes of adjustment of the stroke of the disc-carrying U-frame 77, the connecting rod 100 may be made adjustable, in length, by having its two pivotable ends 106 and 107 screw-threadedly connected to the central portion 100 thereof, with suitable lock-nuts 108 and 109 to lock the ends 106 and 107 at the length-determining setting or adjustment desired.

Directly above the group of discs 83, a diagram-feeding shaft 110 is rotatably mounted in the journal-blocks 111 and 112, which, in turn, are carried on the upper stationary rails 74.

Upon the shaft 110 the diagram-magazine designated generally by the numeral 113 is pivotally mounted, with a stabilizing bracket 114 affixed thereto and extending downwardly and with its lower end 115 screwed to the stationary upper rails 74 (Figure 2 and Figure 6), thereby to keep the diagram-magazine and feeder upright even though pivotally supported upon the shaft 110. The diagram-magazine and feeder may be formed of a pair of side-plates or journal members 116 and 117, which have bearing-openings through which the shaft 110 passes. A pair of frame and spacer rails 118 and 119 extend upwardly from and are affixed to the end bearing-members 116 and 117. To the vertical rails 118 and 119 the front magazine wall 120, the rear magazine wall 121 and the intermediate separator or partition wall 122 are affixed in the manner indicated in Figure 11; the plates or panels 120 and 122 being screwed to the rails 118 and 119 from opposite sides, while the plate or panel 121 has forwardly bent terminal flanges 123 disposed at a right angle to the panel, which are screwed to the rails 118 and 119 from the sides.

A diagram-feed roll 124 of suitable material (perhaps similar to the material of a typewriter roll or the like) may be mounted upon the shaft 110, intermediate the terminal plates 116 and 117, or, the shaft 110 itself may be increased in diameter through its portion which is intermediate the members 116 and 117 so as to act as a paper-feeding or diagram-feeding roll. A guide plate 125 is fastened to the members 116 and 117 at a point slightly below the lower edge of the front panel 120, with its lower edge 126 flared inwardly slightly so as to better feed the diagram-paper to the roll 124. A gap 127 may be left between the upper edge of the plate 125 and the lower edge of the panel 120, so as to expose a part of the diagram at that level. The diagram-roll 124 and the lower edge 126 of the guide-plate 125 are so disposed that when viewed from the front in the direction of the arrow 128 (Figure 10) only a single row or line of the diagram is exposed to view beneath the lower edge 126 of the plate 125, and the so-exposed single line of the diagram will be directly above and in close proximity to the row of turn-projections 85 of the discs 83 as indicated in Figures 9 and 10. The rails 118 and 119 are spaced apart from each other just at the right distance to accommodate the width of the diagram-paper 129, so that the rails 118 and 119 will keep the diagram-paper in vertical alignment with the bank or row of discs 83 and projections 85, as indicated in Figure 9.

The terminal or side plates or members 116 and 117 are provided with an inclined slot 130, into which the trunnions 131 of an idle-roller 132 are adapted to be disposed. The idle-roller 132, bears against the upwardly moving portion of the diagram-paper 129 and serves to keep the paper 129 in the desired path so that it will travel into the rear compartment formed between the plates 122 and 121. A knurled knob 133 is secured to one or both ends of the diagram-paper shaft 110, by means of which the diagram may be advanced, a line at a time, so as to expose successive lines in the manner indicated in Figure 9. If desired, an automatic feed by pawl and ratchet or star wheel and pawl may be applied to the shaft 110 so as to advance the diagram by one line each time the finishing lever 134 is raised for the turning of the balance or remaining discs required to finish the

course of knitting (the operation of the finishing levers 134 and finishing bar 135 being described more in detail hereinafter).

The lower back-turning pawl 87, for turning the discs backwardly towards the initial position after they have been all turned forwardly, is in the form of a bar extending completely across the entire row of discs 83 and is carried from a pair of lugs 136 and 137 which are affixed (by dowel pins, taper pins or otherwise) to the pivot shaft 138 (see Fig. 8). The pivot shaft 138 is, in turn, journalled in the journal blocks 139 and 140 affixed to or carried by the frame 71. A stop lug 141 is also similarly affixed to the shaft 138 with a finger 142 extending outwardly therefrom which serves as a stop member bearing against the cross-bar 143 which extends across the opposed side-frame members 71. The stop-finger 142 serves to limit the upward deflection of the pawl-bar 87. A lever 144 is similarly affixed to the shaft 138, and to its lower end a tension spring 145 is anchored (Figure 2) with the other end of the spring anchored to some stationary part of the machine, so as to exert a constant force upon the lever in the direction of the arrow 146 (Figure 2), thereby exerting a turning force upon the shaft 138 which tends to deflect the pawl-bar 87 upwardly, so that it will enter the notches 86 of the discs 83 when all the notches 86 are in alignment with each other, whereby the entire group of discs are returned to their starting position after the finishing lever 134 has been operated.

From the diagram-feeding shaft 110 an upper pawl-bar 147 (see Fig. 4) is pendently supported by means of the pivotal members 148 and 149 which are journalled on the shaft 110 and are affixed to the ends of the pawl-bar 147. When the U-frame 77 with the discs 83 moves through its forward stroke in the direction of the arrow 80 (Figure 4), such of the turn-projections 85 as have been pushed forward (by the operator) away from the finishing bar 135 against which they initially rest, will slide underneath the pawl-bar 147 (raising it slightly to get past it), and upon the return stroke of the discs 83 (in the direction of the arrow 81) the so-turned projections 85 will be engaged by the lower edge of the pawl-bar 147 thereby automatically turning the projections 85 still further, namely, so that the retaining balls 92 of these discs leave the notches 89 and enter the notches 90, and so that the corresponding push-projections 84 will be deflected into the lower and inoperative positions, below the line of the selector-bars 43.

A manually operated stylus like tool 150 having a thickness no greater than and preferably slightly less than the thickness of a single disc 83, and provided with a shoulder 150a spaced at a pre-determined distance 151 from the free end 152 thereof, is provided. The operator rests this tool upon the finishing-bar 135 and brings it into alignment with the projection 85 to be turned. By then pushing the tool 150 forwardly until the shoulder 150a stops against the finishing-bar 135, the selected projection 85 is turned a distance just sufficient to turn the disc 83 from the engagement of the notch 88 to the engagement of the notch 89 by the retainer ball 92; which advancement turns the push-projection 84 into alignment with the corresponding selector-bar 43.

The pair of finishing-levers 134 are affixed to the pivot-shaft 82 upon which the discs 83 are rotatably mounted, so that by raising one of the levers 134 the other one will raise correspondingly through its interconnection through the shaft 82. One or both of the levers 134 is provided with a handle 153, so that it may be more conveniently raised. The finishing bar 135 extends across the two levers 134 and is affixed to an upward extension or projection 154 on each of said levers 134.

Thus, whether one, two or three colors are used for the pattern-effects in knitting Jacquard-patterned fabric (that is, one, two or three colors in addition to the base-color or body-color), the finishing-bar 135 is advanced, to complete the course, after all preceding colors have been

selected and advanced separately by means of the tool 150 in the manner above described.

The mechanism designated generally by the numeral 155 is a color and course indicator, comprising an outer housing 156 in which is journalled a vertically-disposed shaft 157 carrying a 4-sided light-box 158 with suitably colored translucent plastic or glass windows in each of its four sides corresponding to the four openings 159, 160, 161 and 162 in the front wall of the outer housing 156 of the indicator. To the lower and outer end of the shaft 157 a pinion 163 is affixed. The pinion 163 is preferably directly beneath the rotatable light-box 158, but may be within the housing 156 or just beneath the housing 156. A second pinion shaft 164 is journalled in the base of the housing 156, and to the outer end thereof which extends beneath the housing 156 an eight-pointed star-wheel 165 is secured. This star-wheel is shown, from underneath, in Figure 7.

The color and course indicator 155 may be mounted 20 upon an extension 166 of the upper rail 74 (Figures 6 and 7).

An extension 167 is provided from one of the legs of the U-frame 77 (Figures 6 and 7) and to the underside of this extension 167, a pawl 168 is pivotably mounted 25 at 169. The pawl 168 carries a stop-pin 170 which extends upwardly and fits into a corresponding notch of the extension-bar 167, and a leaf spring 171 having its fixed end anchored to the side of the bar 167 by means of rivets or screws 172, has its free end bearing against 30 the stop-pin 170 of the pawl 168, so as resiliently to urge the pawl 168 into engagement with the star-wheel 165. By this means, each time the U frame 77 with its discs 83 moves through an operating stroke (in the direction of the arrow 80) the pawl 168 turns the star-wheel 165 an eighth of a revolution. The shaft 164 which carries the star-wheel 165 also has affixed through 35 a gear or pinion 173 meshing with the pinion 163 and having twice the diameter or twice the number of teeth, so that for each one-eighth of a revolution which the shaft 164 is turned by the pawl 168, the light-box 158 will be turned one-quarter of a revolution, so as to bring another one of its four sides into juxtaposition to the apertured front face of the housing 156. The light-box 158 is preferably supported at its bottom, upon the gear 40 163, and the upper end of the light box is preferably open, so that a small tubular or other suitable electric light bulb, stationarily supported within the housing 156, from the upper wall thereof, may extend into the revolvable light-box 158 so as to light up the four colored 45 windows provided in each of its four sides.

In addition, light-openings 174, 175, 176, 177, 178 and 179 may also be provided in the front wall of the indicator 155 (facing the operator). These openings may be provided with suitably colored panels corresponding 50 to the colorings of the light-box windows, and another electric bulb positioned behind these openings 175 to 179. An opaque partition may be provided between the electric light bulb which is behind and illuminates the openings 175 to 179, and the light box 158, so that 55 the electric light bulb which is used to illuminate the openings 174 to 179 will not cast any light behind the openings 159 to 162.

The main or drive shaft 26 is caused to revolve a single revolution, after each return stroke of the U frame 77 and discs 83 (in the direction of the arrow 81) and after the operator has selected and turned the next group of projections 85. This is done by the operator stepping on the treadle 180 carried by the arm or lever 181 pivoted at 182 upon the floor-bracket or pedestal 70 183. The lever 181, in turn, pulls down the rod 184 which passes through and is guided by a pair of stationary guides 185 and 186 carried by the lower frame or pedestal 187 of the machine. The down-movement of the rod 184 is against the spring 188 which surrounds 75 a portion of the rod intermediate the lower stationary

guide 186 and the spring-abutment collar 189 affixed to the rod 184 by a set screw or the like. One half of the cylinder comprising the rod 184 is cut away at its upper end so as to present a flat surface 190, and the rod is further recessed along its upper flat portion as at 191, to provide a slight shoulder 192. The upper end of the rod extends through the vertical opening 193 in a clutch box 194, which is provided with a horizontal transverse bearing opening 195. The clutch box 194 is disposed between the forked ends 196 of the lever 197 which is pivoted to the frame 25 of the machine by means of the pivot pin 198. The other end of the lever 197 terminates in a finger 199. A link 200 is pivoted to the other end of the lever 197 by the pivot-pin 201. A clutch arm 202 pivoted to the frame of the machine by means of the pivot pin 203 is, in turn, pivoted to the link 200 by means of the pivot pin 204 so that a turning of the lever 197 in the direction of the arrow 205 causes the lever 202 to be deflected in the direction of the arrow 206, while a deflection of the lever 197 in the direction of the arrow 207 causes the lever 202 to be deflected in the direction of the arrow 208. The lever 202 is provided with a shoulder 209 against which the finger 199 abuts when the lever 197 is deflected in the direction of the arrow 207, so that such deflection will cause the lever 202 to deflect in the direction of the arrow 208, without permitting the link 200 to fold in the opposite direction.

The pulley-wheel 210 is not keyed to but is revolubly mounted on the main or drive shaft 26 and the inner face of the pulley 210 has a pair of lugs 211 facing towards the machine. These lugs are spaced apart from each other so that they form intervening recesses 212 between the spaced-apart ends of the lugs 211.

A clutch hub 213 is keyed to the shaft 26. The hub 213 has a flange 214. A clutch-bolt 215 is slidably mounted in the hub 213 and flange 214, which are recessed to receive the bolt 215. The bolt 215 is provided with a notch 216 in the outermost side thereof, with a wall 217 of the notch inclined or flared. A helical compression spring 218 is interposed between the bolt 215 and an abutment plate 219 secured to the hub 213 by means of the screw 220, so as resiliently to urge the bolt 215 in the direction of the arrow 221, namely, in the direction of the pulley-wheel 210 and the lugs 211 and recesses 212 thereof. In order to accommodate a spring 218 of adequate number of convolutions, the bolt 215 is provided with a hole or recess of sufficient depth in which a part of the spring 218 is recessed or housed.

The free end 222 of the clutch lever 202 is curved to the curvature of the hub 213, and the end 223 thereof is thinned out so as to permit it wedgingly to enter into the notch 216 of the clutch-bolt 215 by engaging the inclined entrance-surface 217 thereof. When the clutch-lever 202 is in its bolt-engaging or power-off position shown in Figure 13, its leading edge 223 enters the notch 216 of the bolt 215 and so retracts it until the end of the bolt 215 which faces the pulley wheel 210 is fully withdrawn, flush with the surface of the flange 214. When however the clutch lever 202 is deflected in the direction of the arrow 206 (by the deflection of the lever 197 in the direction of the arrow 205) it is withdrawn from the circular path of the bolt 215, so that the bolt 215 is instantaneously projected into its operative position shown in Figures 21 and 22, and thus enters the next recess 212 on the face of the pulley-wheel 210 and is engaged by the next approaching lug 211. By this engagement, the hub 213 and flange 214 are rotated and hence the shaft 26 to which they are keyed is rotated. If the clutch lever 202 were kept so retracted, the shaft 26 would be rotated several or many revolutions. However, the arrangement of the rod-clutch mechanism shown in Figures 14 to 18 inclusive, together with the knock-off mechanism shown in Figures 12 and 13, is such that when the hub 213 and flange 214 have been revolved

through one revolution (or, indeed, just before they have completed one revolution) the clutch lever 202 is again deflected in the direction of the arrow 208 into the path of the oncoming bolt 215 so as to re-enter the notch 216 thereof and thereby withdraw the bolt 215 from operative engagement with the pulley wheel 210. The clutch lever 202 has a stop-lug 224 affixed thereto, facing the inner end 225 of the bolt 215, and in alignment therewith, so that when the lever 202 is in its position shown in Figure 13, the inner end 225 of the bolt 215 will be brought to a stop by the lug 224, thereby bringing all power driven parts of the machine to a standstill at a predetermined point of their operative cycle. The lug 224 is preferably recessed slightly into the face of the lever 202, or is given lateral support by the shoulder 226 formed on the lever, and is bolted thereto by means of the bolt 227.

The rod-clutch-box 194 is pivoted between the forked ends 196 of the lever 197 by means of the cylindrical clutch pin 230, which is provided with a notch or a cut-out 231 to approximately one-half the diameter of the pin, for a length and in a position corresponding to the location of the half-round portion of the rod 194. An arm 232 is keyed or pinned to the cylindrical clutch-pin 230, so that a deflection of the arm 232 will cause the clutch-pin to revolve or to be turned correspondingly.

A helical compression spring 233 is interposed between the turned end 234 of the arm 232 and the lower side of the lever 197. Small spring-anchoring or spring-retaining recesses 235 and 236 may be provided for the arm-end 234 and in the lever 197, respectively, so as to keep the spring in position.

The force of the spring 233 upon the arm 232 urges the clutch pin 230 to rotate or turn it in the direction of the arrow 237 so as to cause its clutching edge 238 to engage beneath the shoulder 192 formed in the half round portion of the rod 184 in the manner indicated in Figure 17. In this position a down-pull upon the rod 184, by means of the treadle 180, will cause a downward deflection of the forked end of the lever 197, in the direction of the arrow 205 and will, in turn, deflect the clutch-lever 202 in the direction of the arrow 206 so as to withdraw the clutch-lever from engagement with the clutch-bolt 215 and to permit the latter to enter into driving engagement with the pulley wheel 210. The knock-off lever 239 is pivoted to the machine frame member 25 by means of the pivot bolt 240. The end 241 of the lever 239 is in vertical alignment with the flange 214 carried by the clutch-hub 213 and, more particularly, is in alignment with a knock-off projection 242 carried by and projecting from said flange. The other end 243 of the knock-off lever 239 has an adjustable abutment 244 thereon, which may be made in the form of a screw threaded through the lever-end 243 and held in any desired setting or adjustment by means of a lock-nut 245. The end of the screw 244 is in alignment with the underside of the end of the arm 232. The projection 242 is so positioned in relation to the position of the clutch-bolt 215 and the lever-end 241, that the projection 242 will strike and deflect the lever end 241 in the direction of the arrow 246 by an amount sufficient to deflect the arm 232 and to turn the clutch pin 230 out of clutch-engagement with the half-round portion of the rod 184. Thus released from the down-pull of the rod 184, the lever 197 is at once deflected upwardly in the direction of the arrow 207, by means of the helical compression spring 247 which is interposed between the forked ends 196 of said lever 197 and the upper stationary rod-guide 185 (a washer 248 intervening the upper end of the spring 247 and the forked ends 196 of the lever 197). When so deflected upwardly in the direction of the arrow 202 (when so released from the downward pull of the lever 184) the lever 197 again deflects the clutch-lever 202 into the path of the clutch-bolt 215 so that when the bolt 215 approaches the end 223 of the clutch lever 202 said end enters the notch 216

of the bolt 215 and withdraws it from driving engagement with the pulley-wheel 210. The momentum of the machine is just sufficient to bring the end 225 of the clutch-bolt 215 into abutting engagement with the stop-lug 224 of the face of the clutch lever 202, thereby stopping all power-driven parts of the machine at the same point of their cycle after each revolution of the shaft 29.

The pulley wheel 210 preferably has a V groove in its periphery or may have a flat surface, to receive the endless belt 249 which will be a V belt if the pulley is a V pulley or a flat belt if the pulley is a flat pulley.

A suitable electric motor (not shown) is disposed underneath, with its pulley in alignment with the pulley 210, and with the belt 249 traveling over a motor-pulley.

For better readability, the design-diagram or pattern-diagram 129, has its successive blocks colored with the various colors of the yarn to be used for the stitches indicated by the particular blocks on the diagram.

While in the foregoing description and the accompanying drawings, the specific illustration given is that mechanism which would accommodate three colors in addition to the base-color or body-color of the fabric, yet the mechanisms (and the principles of the mechanisms) of the present invention are capable of being used with larger number of colors, if desired, and may also be used for punching the pattern-control cards, sheets, tapes or webs to be used for controlling variables other than color (in knitting, weaving and other machines).

If a total of five colors were used (including the base-color or body-color) then instead of having merely four changing lights (159 to 162) there would be five such changing lights, one for each of the five colors, and so on. In that case, however, a five-sided light-box 158 would be used, and a ten-point star-wheel 165 would be used, so as to turn the light-box 158 a fifth of a revolution with each advancement of the U-frame 77 and discs 83.

In the following claims, the term "selector element" or "selector" has reference to the discs 83 or their equivalents, while the terms "punch-activating elements" and "punch-activator" have reference to the bars 43 or their equivalents (namely, to the element in the punching-machine which in one position activates its corresponding punch and in another position leaves the punch idle).

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having described the invention, I claim the following:

1. Selector mechanism for jacquard-punching machines and the like, said selector mechanism including a plurality of individually and selectively movable selectors for actuating corresponding punch-activating elements of said jacquard-punching machine, each of said selectors having an initial or retracted inoperative position, an operative

position, and a second inoperative position, means for automatically reciprocating said selectors in unison, means for causing said selectors to move from their operative positions to their second inoperative positions by the return stroke of said reciprocatory motion, and means for automatically moving said selectors in unison from the last-mentioned position to their initial inoperative positions by any return stroke of the aforesaid reciprocatory motion if such return stroke follows the arrival of all selectors in the aforesaid second inoperative position.

2. Selector mechanism for jacquard-punching machines and the like, said selector mechanism including a plurality of individually and selectively movable selectors, each having an initial or retracted inoperative position, an operative position, and a second inoperative position means for reciprocating said selectors in unison, means for causing said selectors to move from their operative positions to their second inoperative positions by the return stroke of said reciprocatory motion, and means for moving said selectors in unison from the last-mentioned position to their initial inoperative positions by any return stroke of the aforesaid reciprocatory motion if such return stroke follows the arrival of all selectors in the aforesaid second inoperative position, a multi-colored illuminated color and course indicator having a plurality of positions, and means for moving said indicator from one of its positions to its next successive position with each aforesaid reciprocatory cycle.

3. A method for selectively actuating the punch-activators of a jacquard-punching machine and the like which comprises independently and selectively moving selector elements corresponding to each punch-activator of the jacquard-punching machine from their retracted inoperative positions to their operative positions wherein said selector elements are in operative alignment with the punch-activators, automatically moving said selector elements in unison from their operative positions to second inoperative positions in the same direction as that of their aforementioned selecting motion, and then automatically moving said selector elements in unison from said second inoperative positions to their initial inoperative positions in a direction opposite to that of the first two motions, whereby the same selector element cannot remain in its operative position during more than one stroke of the punching machine nor be moved into its operative position more than once unless and until all the selector elements which have been moved into their operative positions have first been returned to their initial inoperative positions.
